UNITED STATES PATENT OFFICE.

IDA O. MAGNUSON, OF SMOLAN, KANSAS.

HAIR-FASTENER.

1,274,920.

Specification of Letters Patent.

Patented Aug. 6, 1918.

Application filed January 24, 1918. Serial No. 213,570.

To all whom it may concern:

Be it known that I, IDA O. MAGNUSON, a citizen of the United States, residing at Smolan, in the county of Saline and State 5 of Kansas, have invented certain new and useful Improvements in Hair-Fasteners, of which the following is a specification.

This invention relates to hair pins or fasteners, and the object is to provide a fastener of this character which is both useful and ornamental and when applied will remain in position and impart a secure feeling to the hair of the wearer.

Another object is to provide a device of 15 this nature which is simple in construction and cheap to manufacture.

With the foregoing and other objects in view, which will appear as the description proceeds, the invention resides in the combination and arrangements of parts and in the details of construction hereinafter described and claimed, it being understood that changes in the precise embodiment of the invention herein disclosed may be made 20 within the scope of what is claimed without departing from the spirit of the invention.

In the accompanying drawings:—

Figure 1 represents a front elevation of 30 the device constituting this invention, Fig. 2 is a rear elevation thereof, and Fig. 3 is an edge view.

In the embodiment illustrated the hair pin or fastener 1 constituting this invention is composed of a piece of wire of any suitable or desired length according to the length of the pin it is desired to make, and which is bent midway its ends into a loop shown at 2. This looped portion 2 is then 35 bent inwardly as shown at 3 to form a hook-like member 4 which is arranged in a plane parallel with the legs 5 of the hair pin as is shown clearly in Fig. 3 and has mounted thereon a head 6. This head 6 may be composed of any suitable or desired material 40 and ornamented in any desired manner and as here shown, it has its edges turned inwardly to form clamping elements 7 which are engaged with the side bars of the hook

4. This head 6 is provided at its outer end 50 with pocket-like recesses 8 to receive clamping fingers 9 formed in the legs 5 of the hair pin adjacent the bend 3 therein. These fingers 9 are formed as here shown by bending the legs inwardly toward each other as 55 shown in Fig. 2, and these fingers are designed to clampingly engage the hair when the pin is inserted and hold it reliably in position.

While this device is described as constructed of metal it is obvious that it may be composed of celluloid, bone or similar material if found desirable.

The head 6 as here shown conforms to the shape of the hook member 4, being substantially triangular, although obviously the configuration thereof may be varied if found desirable to do so.

This device while very simple to construct and cheap to manufacture presents an ornamental appearance when placed in position and also operates to securely hold the hair in place.

From the foregoing description, taken in connection with the accompanying drawings, the advantages of the construction and of the method of operation will be readily apparent to those skilled in the art to which the invention appertains and while I have described the principle of operation of the 75 invention together with the device which I now consider to be the best embodiment thereof, I desire to have it understood that the device shown is merely illustrative and that such changes may be made as are within 80 the scope of the claimed invention.

I claim:—

1. A hair fastener comprising a piece of wire having two prongs with a hook extending parallel therewith, a head carried by 90 said hook having side pockets, the prongs adjacent said head having inwardly projecting clamping fingers positioned to coöperate with said pockets to clamp the head.

2. A hair fastener comprising a pair of 95 prongs having a loop-like hook member arranged parallel with the prongs, a head carried by said hook member composed of a

plate having inturned edges clampingly engaged with the side bars of the hook and having pockets in its outer end at its opposite sides, and clamping fingers carried by 5 said prongs in position to enter said pockets to clamp the hair between them and the walls of the pockets.

In testimony whereof I affix my signature in presence of two witnesses.

IDA O. MAGNUSON.
